PAIR OF SPECTACLES

Donald J. McCulloch, Greece, N.Y., assignor to Bausch & Lomb Incorporated, Rochester, N.Y., a corporation of New York

Filed Sept. 13, 1965, Ser. No. 86,954

Term of patent 14 years

(Cl. D57—1)

FIG. 1 is a front view of a pair of spectacles showing my new design;

FIG. 2 is a side view of said spectacles taken from the left side thereof as viewed in FIG. 1; and

FIG. 3 is a top view of said spectacles.

My design for the pair of spectacles disclosed is characterized by the surface ornamentation applied to the frame front as shown.

The side not shown has substantially the same appearance as the side shown. The temple portion is shown broken away in FIG. 3 for convenience of illustration.

I claim:

The ornamental design for a pair of spectacles, substantially as shown and described.
